FIG. 3.

UNITED STATES PATENT OFFICE.

JOHN BURNS, OF CHICAGO, ILLINOIS.

KNOCKDOWN COOP.

SPECIFICATION forming part of Letters Patent No. 291,027, dated January 1, 1884.

Application filed October 12, 1883. (No model.)

To all whom it may concern:

Be it known that I, JOHN BURNS, a citizen of the United States, residing at Chicago, county of Cook, and State of Illinois, have 5 invented new and useful Improvements in Knockdown Coops, of which the following is a specification, reference being had to the accompanying drawings, illustrating the invention and improvement, in which—

10 Figure 1 is an isometrical representation of my new and improved coop put up in the form for transporting chickens or general poultry; Fig. 2, an isometrical view of the top and ends of the coop placed vertically over 15 the sides and bottom, preparatory to the parts being united to form the coop shown at Fig. 1. Fig. 3, Sheet 2, shows an end view of the parts in knockdown form for return shipment; Fig. 4, a side elevation of the parts in 20 knockdown form.

The present invention relates to an improvement in coops for shipping poultry, which are to be so manipulated for return shipment as to occupy a smaller space than where set 25 up for transporting poultry.

The invention in brief consists in a slatted top part hinged to slatted end parts, and a bottom part hinged to slatted side parts, the end parts being tongued into the side parts, 30 and the upper and lower sections held together by hooks. The lower inside portions of the end parts are provided with cross-pieces, which serve to support the bolts which hold the coop in a knockdown form, and 35 serve to hold the end parts level in a knockdown form; and the top is provided with a slip-slat for the removal of the poultry.

A represents the top part of the coop, which is composed of strong end rails, B B, and 40 side stiles, C C, halved together at their ends, and secured by wrought nails clinched. A middle rail, D, is also halved onto the stiles C, and gained into these three rails are the top slats, e e, &c., the middle slat, f, being 45 made to slide in guides a a, attached to the rails B B D, that access may be had to the inside of the coop. To this top part thus formed are hinged, at m m, end parts, E, which are composed of strong top and bottom rails, F G, and stiles H H, which are

halved together at their ends, and secured by wrought nails driven through and clinched. The stiles H H are provided with tongues I I on their outer edges, respectively, for uniting with the sides J J by means of grooves b b, formed therein, and gained into and fastened to the outsides of the stiles H are slats d d. 55

The sides J are composed of stiles L L L and rails M M, united similarly to those stiles and rails aforementioned, and are slatted at g g similarly to the ends E.

The bottom T is composed of long sills P P, halved to short sills R R R, and secured by clinched wrought nails. The short sills projecting above the long sills provide room for 65 the bottom boards, S S, between the sides J and the sills P P.

The top A is hinged to the ends E at m, and the sides J are hinged to the bottom T at h, so that the ends will fold under the top A, 70 and the sides fold onto the bottom T, when the crate is in knockdown form, as shown at Figs. 3 and 4, Sheet 2. That the ends E may fold parallel with the top A, their inside lower parts have attached thereto cross-pieces U U, respectively, which serve the 75 purpose of carriers for the bolts w, which hold the coop firm in a knockdown shape, holes x being made in the cross-pieces for that purpose. When the crate is knocked down, 80 the bolts w are put through the holes x in the top and bottom cross-pieces. The two main sections of the coop are held in the shape shown at Fig. 1 by hooks and screws n p, of ordinary construction. The advantage of this 85 construction is its cheapness and simplicity of construction, and especially the rapidity with which it can be knocked down and set up; and in this respect I have overcome the objections which are found in other coops. In 90 practice the rails and stiles for a forty-four inch coop should be one inch by one and one-half inch stuff, and the slats one-half inch thick by one and one-half inch wide. I consider elm to be the best wood for the construction.

I claim as new and desire to secure by Letters Patent of the United States—

A knockdown coop consisting of two main parts or sections, the upper one of which com- 100

prises the top A, hinged to the ends E, the cross-pieces U U, tenons I I, and sliding slat f, and the lower section, comprising the bottom T, hinged to the sides J J, the two sections being combined by means of the tongues I I, grooves g, and hooks and screws n, and the said sections constructed, as shown, to be folded in knockdown shape, and be held in position

by the bolts w w, substantially as shown and described.

September 12, 1882.

JOHN BURNS.
